C. F. P. CARRIER.
INDICATING DEVICE FOR THERMAL CUT-OUTS.
APPLICATION FILED APR. 28, 1920.

1,368,482.

Patented Feb. 15, 1921.

UNITED STATES PATENT OFFICE.

CARL F. P. CARRIER, OF PHILADELPHIA, PENNSYLVANIA.

INDICATING DEVICE FOR THERMAL CUT-OUTS.

1,368,482.

Specification of Letters Patent. Patented Feb. 15, 1921.

Application filed April 28, 1920. Serial No. 377,243.

To all whom it may concern:

Be it known that I, CARL F. P. CARRIER, citizen of the United States, residing at Philadelphia, in the county of Philadelphia and State of Pennsylvania, have invented 5 certain new and useful Improvements in Indicating Devices for Thermal Cut-Outs, of which the following is a specification.

My invention relates broadly to improvements in fuse-indicators, and has for its object to provide a novel construction, with a lamp socket, of elements whereby the usual disadvantages consequent to the rupture and consequent renewal of the fusible 15 element are eliminated.

A further object of my invention is the provision of a signaling device adapted for repeated use, which device is operable by the rupture of the fusible element, and 20 which also furnishes the necessary illumination for the renewals of the ruptured element.

A still further object of my invention is the provision of means forming an accessible 25 and compact part of the lamp socket, said means being adapted for repeated renewals of the fusible element and which also carry the renewal fuse unit.

Further objects of my invention relate to 30 various details of construction and arrangement of parts hereinafter described and particularly set forth in the accompanying drawings, wherein:

Figure 1 is a side elevation, partly in section, illustrating my invention adapted for 35 use wherever "plug type" fuse units are used.

Fig. 2 is a side elevation, partly in section, illustrating my invention adapted for 40 use wherever "cartridge type" fuse units are used.

Fig. 3 illustrates my invention slightly modified to adapt it to one form of standard fitting.

Fig. 4 illustrates my invention slightly modified to adapt it to another form of standard fitting.

Fig. 5 is an end elevation of Fig. 4.

Fig. 6 illustrates my invention as adapted

to use wherever thermal cut-outs are used 50 to indicate or open an electric circuit when a predetermined degree of heat is reached external to the circuit; and

Fig. 7 is a detailed view of the thermal unit illustrated in operative position in 55 Fig. 6.

Fusible cut-outs as commonly employed in electrical work, consist of a short length of fusible material, electrically connected at its ends to suitable terminals, and the fusible 60 material inclosed within a shell of non-combustible insulating material. It is also common practice to substitute for the fusible material, a length of non-fusible conducting material secured at its ends to terminals by readily fusible solder. In each case, however, the fuse element operates to break the circuit between the terminals when a predetermined degree of heat is reached; such heat obviously occurring 70 from an overload on the line, or from an external source, as for instance, when a fuse unit is mounted on a journal box, motor housing, etc.

To comply with the requirements of the 75 fire underwriters, the fusible element must necessarily be inclosed, and much difficulty is therefore experienced in ascertaining whether or not the fusible element is ruptured, for it will be readily appreciated that 80 when a plurality of fuse units are employed in a series of related circuits, as is generally the case, it is an exceedingly troublesome and time-consuming practice to locate a blown or ruptured fuse, since each fuse 85 unit must be removed, and the circuit tested. On locating the blown fuse, it is either replaced by a new fuse unit, or the ruptured fusible element is removed from the shell 90 and a new length of fusible material inserted between the terminals; or said fusible element may be resoldered in order to complete the circuit. The latter methods are more desirable in use in that the renewing operation requires little or no experience or 95 expense, and the necessity of maintaining a supply of fuse units in reserve for immediate use is thus obviated.

It will also be noted, that when lamps are wholly depended upon for the illumination of switch boards, circuits, etc., a ruptured fuse in the lamp supplying circuit will present further difficulties, and dangers, since the blown fuse must be located and repaired in the dark.

Numerous attempts have heretofore been made to provide a fuse of this character with suitable indicating means whereby an attendant may tell at a glance the condition of the fusible element. The results of such attempts, however, have not proven wholly satisfactory, due to their complicated construction, their unreliability, and the consequent difficulty of use and expense of manufacture.

To obviate the above referred to disadvantages and provide numerous advantages heretofore unattainable with indicating fuse units such as are at present on the market, I construct a lamp socket 1, with suitable terminals 2 and 3, adapted to receive and contact correspondingly formed terminals 4 and 5 of the lamp 6. Suitably connected with the terminals 2 and 3 are a pair of lead terminals 7 and 8, the lead terminals 7 comprising a cylindrical threaded shell connected with the base of the lamp socket 1, through which the lead terminal 8 extends, and is insulated therefrom by a removable diaphragm 9 of any suitable insulating material.

Screw threads 10, are formed on the lead terminal 8, on which a thumb nut 11 operates to engage and clamp one end of a length of fusible material 12, the other end of the fusible element, being clamped between the removable insulating diaphragm 9 and the lead terminal 7.

It will thus be seen that a circuit is completed between the lead terminals 7 and 8, through the fusible element 12, and that the terminals 5 and 4, are connected in parallel with the lead terminals 7 and 8.

In operation, the current supplied to a circuit in which the lead terminals 7 and 8 are connected, normally traverses the fusible element 12. If, however, for any reason, an over-load occurs in the circuit and causes the fusible element 12 to blow, the current is shunted through the filament 13 in the lamp 6. The illumination of the lamp 6 indicates that the fusible element is ruptured, and the lamp remains lighted until the fusible element is renewed.

To facilitate the renewal of the fusible element 12, I provide a bobbin 14, forming an extension of the lamp socket 1 on which fusible material 12^a is wound in reserve for repeated renewals of the fusible element, suitable lengths of the fusible material 12^a being severed from the supply on the bobbin 14 when needed, and connected to the lead terminals 7 and 8, as above described.

My invention is also applicable to numerous embodiments, as illustrated in Figs. 2 to 6.

In Fig. 2, a standard type of renewable cartridge fuse consisting of a cylindrical insulating shell 15, having terminals 16 and 17 is adapted to connect a suitable length of fusible material 12 between the terminals 16 and 17, which are respectively connected with the lead terminals 8^a and 7^a of the lamp socket 1^a. The insulating shell 15 is removably secured in the terminals 16 and 17, by a screw-threaded plug 18, which engages screw threads 19 on the inner diameter of the terminal 16.

In Fig. 3, I have illustrated my invention as applied to a standard "plural lamp socket," comprising a lamp socket 1^b, and a fuse socket 19, the fuse socket 19 forming a portion thereof and extending at right angles thereto, the terminals 2^b and 3^b of the lamp socket 1^b, being respectively connected with the lead terminals 7^b and 8^b, and the terminals 2'^b and 3'^b of the fuse socket 19 being connected in parallel with the terminals 2^b and 3^b. A fuse unit 20 having terminals 21 and 22, adapted to respectively connect with the terminals 2'^b and 3'^b of the fuse socket 19, is preferably of the standard "plug type" having a fusible element 12^b connecting the terminals 21 and 22.

In Figs. 4 and 5, I have illustrated my invention slightly modified to permit the use of cartridge fuse units 23 of standard form. A pair of terminals 7^c and 8^c of resilient conducting material are connected adjacent the base of the lamp socket 1^c, with the terminals 2^c and 3^c of the lamp socket, the fuse unit 23 comprising a shell of insulating material, through which extends a fusible element indicated at 12^c, and connected at its ends with the terminals 26 and 27 of the fuse unit 23. Depending from the base of the lamp socket 1^c is a spring clip 24 having resilient arms 24 and 25, the arms 24 and 25 being adapted to engage the insulating shell of the fuse unit 23, and retain the terminals 26 and 27 in contact with the resilient terminals 7^c and 8^c, respectively, of the lamp socket 1^c.

In the figures above described, I have illustrated my invention as adapted to be used in electrical circuits wherever a fuse unit is required for the protection of the circuit against overload, or an excess of current arising from any source.

In Fig. 6, however, my invention is illustrated as applied to thermal cut-outs, where the thermal element operates to break or open a circuit, and to indicate when a predetermined degree of heat is reached; such heat being generated at a point external to the circuit. I have illustrated my invention as adapted for attachment to journal 180

boxes, water jackets of internal combustion engines, electric motors, etc.

When used in connection with electric motors or other electrical apparatus, such as coils, etc., the functioning of the thermal element may operate to break the circuit feeding such apparatus.

The lamp socket 1^a is formed with the usual terminals 2^a and 3^a, adapted to receive 10 and contact the terminals 4^a and 5^a of the lamp 6^a. A hollow base member 28 is connected to the lamp socket 1^a, and is provided with perforated bosses 29 and 30, in which retaining means such as bolts are 15 adapted to clamp the base 28 to such apparatus as above mentioned.

Lead wires 31 and 32 connected to a source of electricity extend through perforations in the base member 28, and are connected respectively with the terminals 33 and 34. 20 Slots 35 and 36 are respectively formed in the terminals 33 and 34, in which screws 37 and 38 operate to retain the terminals in position in the base 28. A block of insulating material 39, in which the screw 37 is threaded serves to insulate the terminal 33 from the base 28, respectively connecting the terminals 2^a and 3^a of the lamp socket 1^a, and extending downwardly therefrom 25 are a pair of lead terminals 40 and 41, said lead terminals 40 and 41 being formed of resilient conducting material and adapted to contact the upper surfaces of the terminals 33 and 34 respectively.

30 A fuse element 12^a which is shown by illustration as a non-fusible link connected at its ends with the terminals 33 and 34 by readily fusible solder 42, is adapted to normally complete the circuit between the terminals 33 and 34.

35 It will be readily understood from the foregoing that when a predetermined degree of heat is transferred to the terminals 33 and 34, from the base 28, the solder 42 will melt, 40 releasing the link 12^a from the terminals 33 and 34. The link 12^a will then drop under 45 the force of gravity through the hollow base 28, as indicated in dotted lines and open the circuit between the lead wires 31 and 32, 50 shunting the current through the lamp 6^a, as above described.

I am aware that some changes other than those already indicated, may be made in the various arrangement and combinations of 55 the several devices and parts, as well as the details of construction thereof, without departing from the scope of my present invention. Hence I do not limit my invention to the exact arrangements and combinations of 60 said devices and parts as described in the foregoing specification, nor do I confine myself to the exact details of the construction of said parts as illustrated in the accompanying drawing, it being appreciated that 65 those skilled in the art may make various

modifications without departing from the spirit of my invention.

Having thus described my invention what I claim as new and desire to secure by Letters Patent is:—

70 1. In a device of the character described, in combination, a lamp socket having lead terminals, and a thermal cut-out carried by said lamp socket and connected in parallel with said lead terminals.

75 2. In a device of the character described, in combination, a lamp socket having lead terminals, and a thermal cut-out carried by said lamp socket, said thermal cut-out comprising a fusible element adapted to bridge 80 the lead terminals on said lamp socket.

85 3. In a device of the character described, in combination, a lamp socket having lead terminals, a thermal cut-out carried by said lamp socket, said thermal cut-out having 85 terminals connected in parallel with said lead terminals, a fusible element bridging said terminals, and means for renewing said fusible element.

90 4. In a device of the character described, in combination, a lamp socket, lead terminals carried by said lamp socket, and a thermal cut-out connected in parallel with and carried by said lead terminals.

95 5. In a device of the character described, in combination, a lamp socket having lead terminals, a fuse unit comprising a fusible element connected in parallel with said terminals and carried by said lamp socket, and means for repeatedly renewing said 100 fusible element.

105 6. In a device of the character described, in combination, a lamp socket having lead terminals, a fuse unit having a fusible element connected in parallel with said terminals and carried thereby, means for repeatedly renewing said fusible element, comprising a bobbin mounted on said lamp socket and fusible material carried by said 110 bobbin.

115 7. A device of the character described, in combination, a lamp socket, a fuse unit, and means for renewing said fuse unit, said lamp socket having lead terminals, terminals on said fuse unit, a fusible element connecting said terminals, which are in turn connected in parallel with said lead terminals, and fusible material carried by said lamp socket for renewing said fuse unit.

120 8. In a device of the character described, in combination, a lamp socket and a lamp, lead terminals connecting said lamp socket, a fuse unit connected in parallel with said lead terminals, comprising terminals, and a fusible element connecting said terminals, 125 whereby fusion of the fusible element will operate to light said lamp, and means carried by said lamp socket and operable to renew said fusible element and extinguish said lamp.

9. In a device of the character described, in combination, a lamp socket having terminals, a fuse socket formed in piece therewith and having terminals connected in parallel with the terminals in said lamp socket, a plug fuse having terminals adapted to contact said terminals in said fuse socket and lead terminals on said lamp socket connected in parallel with said terminals in said fuse 10 socket.

10. In a device of the character described, in combination, a lamp socket having terminals, resilient conductors carried by said socket and connected with said terminals, a fuse unit having terminals adapted to contact said resilient conductors and means detachably securing said fuse unit to said socket. 15

In testimony whereof I affix my signature.
CARL F. P. CARRIER.
